CLAIM

The ornamental design for an electronic-trip, molded-case circuit breaker, as shown and described.

DESCRIPTION

FIG. 1 is a top perspective view of an electronic-trip, molded-case circuit breaker showing our new design; FIG. 2 is a left end elevational view thereof; FIG. 3 is a right end elevational view thereof; FIG. 4 is a front elevational view thereof, the rear elevational view being a mirror image; FIG. 5 is a top plan view of an electronic-trip, molded-case circuit breaker showing our new design on an enlarged scale; and FIG. 6 is a bottom plan view thereof.

FIG/FIG. 2FIG. 3FIG. 4FIG. 6FIG. 5
